UNITED STATES PATENT OFFICE.

JOHN HENRY LAMB, OF KIDDERMINSTER, ENGLAND.

DESIGN FOR A CARPET.

Application filed April 27, 1923. Serial No. 5,975. Term of patent 14 years.

To all whom it may concern:

Be it known that I, JOHN HENRY LAMB, a subject of the King of Great Britain, residing at Kidderminster, in the county of Worcestershire, in the Kingdom of England, have invented a new, original, and ornamental Design for a Carpet, of which the following is a specification, reference being had to the accompanying drawing, forming part thereof.

The figure is a plan view of a carpet, showing my new design.

I claim:

The ornamental design for a carpet, as shown,

JOHN HENRY LAMB.
